UNITED STATES PATENT OFFICE.

ALBERT E. VANDERCOOK, OF ALAMEDA, CALIFORNIA, ASSIGNOR TO CALIFORNIA MACVAN COMPANY, A CORPORATION OF CALIFORNIA.

THICKENER.

1,182,514.

Specification of Letters Patent.

Patented May 9, 1916.

Application filed July 21, 1914. Serial No. 852,162.

To all whom it may concern:

Be it known that I, ALBERT E. VANDERCOOK, a citizen of the United States, and a resident of Alameda, county of Alameda, 5 and State of California, have invented certain new and useful Improvements in Thickeners, of which the following is a specification.

The invention relates to thickeners or de-waterers which are employed for separating the solid or semisolid material from the liquid or pulp containing the same.

The object of the invention is to provide a thickener which is highly efficient in operation.

Another object of the invention is to provide a thickener in which force is continuously applied to the settled material to move it toward the outlet.

Another object of the invention is to provide means in a thickener for preventing the escape of the heavier material after it has been collected.

Another object of the invention is to provide means for compressing the collected material before it is discharged.

A further object of the invention is to provide a thickener in which the weight of the material in the thickener assists in moving the collected material toward the outlet.

The invention possesses other advantageous features some of which, with the foregoing, will be set forth at length in the following description, where I shall outline in full that form of the invention which I have selected for illustration in the drawings accompanying and forming part of the present specification.

In the drawings I have shown only one specific form of my generic invention, but it is to be understood that I do not limit myself to such form because my invention may be embodied in a multiplicity of forms, each being a species of my said invention. It is also to be understood that by the claims succeeding the description of my invention, I desire to cover the invention in whatever form it may be embodied.

Referring to said drawings: Figure 1 is a vertical section of the thickener. Fig. 2 is a cross section taken on the line A—A Fig. 1.

The thickener of my invention is particularly adapted to be used in metallurgical operations, for separating the solid and semi-

solid material from ore pulp, and I shall describe it in this connection herein, but it is to be understood that it may be used in other operations in other industries for dewatering or thickening pulp or similar masses. In metallurgical work the ore pulp consists of ground or pulverized ore and a large percentage of water or solution, and it is desirable to reduce the percentage of water or solution in the pulp. The ore particles are of heavier specific gravity than the water or solution in which they are contained, and settle through the liquid, and the purpose of the thickener is to collect the settled ore particles and remove them from the liquid.

The thickener comprises a tank 2, preferably cylindrical in shape, provided at the center of the bottom with a discharge outlet 3, which is controlled by a valve 4. Arranged concentrically in the tank and projecting above the upper edge thereof is a shaft 5 which is supported on suitable bearings 6 arranged on the frame or structure 7 which is arranged above the tank. The structure 7 is removably secured to the cross beams 21 which are secured to the top of the tank and attached to the upper end of the shaft 5 is a clevis 22 for receiving a hook which may be employed for raising the shaft and its attached mechanism out of or above the bottom of the tank. Secured to the shaft 8 is a worm wheel 8 which is driven by the worm 23 mounted on the frame 7. Arranged at the lower end of the shaft and supported thereby, by suitable rods or bars 9, and rotatable with the shaft, is the settled material gatherer which preferably consists of two spiral blades 11—12, the spirals being arranged close to and parallel with the bottom of the tank and the blades thereof being preferably vertically disposed. The bottom of the tank is preferably substantially horizontal or flat and the blades are preferably substantially flat spirals. One spiral is advanced 180 degrees with respect to the other, producing a balanced construction, but it is evident that only one spiral may be employed when desirable. Each spiral preferably subtends an angle of 360 degrees or more, so that the material is gradually moved toward the center by the rotation thereof. When the shaft is slowly rotated the settled material is gradually and continuously moved toward

the discharge opening in the center of the tank. The spirals are preferably constructed in such manner that the succeeding turns thereof, progressing inwardly, lie closer together, that is, the distance between the succeeding turns decreases inwardly. This produces a more efficient thickening or dewatering of the pulp, by moving the settled particles into smaller space, thereby expelling the liquid and producing a thicker mass. When a particle of settled material is caught by a slowly rotating spiral blade, the particle is moved inward toward the center continuously and is not moved inward in a 15 step-by-step motion as has been heretofore proposed. This continuous movement of the settled material toward the center, not only increases the rate at which the material is gathered, but also increases the rate at which it settles, since the movement of the continuous blades does not agitate the material in the tank. Arranged over the inner ends of the spirals and preferably secured thereto or to the bars 9, is a plate 13, which bears 25 against the upper edge of the spiral and rotates therewith and under which the collected material is conveyed by the spirals. This plate, which is preferably concentric with the discharge outlet prevents the thick 30 mass from being crowded upward above the level of the spirals as it approaches the center and in that manner increases the efficiency of the thickener and also assists in forcing the mass through the outlet. It 35 is preferable, though not essential, that the spirals extend under the plate, and the inner ends of the spirals may terminate at the periphery of the plate when desirable, although this construction will 40 not produce so efficient a thickener as the construction illustrated. The plate sustains the pressure of the liquid in the tank at the center, so that vertical pressure downward is not exerted on the mass below 45 the plate. The pressure on this mass is laterally or radially inward, thereby forcing the material toward the outlet.

Arranged above the plate 13 and surrounding the shaft 5 is a cap or deflecting plate 14, preferably formed as a cone, which prevents the deposit of the ore particles on the plate 13, and deflects the entering material outward radially. The material to be thickened is preferably fed into the tank 55 through the concentric conduit 15, which terminates at its upper end above the top of the tank. The pulp may be conveyed to the conduit 15 by the launder 16. Surrounding the tank at its upper edge is an overflow 60 launder 17 provided with a discharge pipe 18.

In operation, pulp is flowed continuously into the tank and the settled ore particles are caught by the revolving spirals and 65 moved continuously inwardly toward the

center of the tank. The mass of particles gradually becomes more thick as it approaches the center and is discharged either continuously or intermittently through the outlet in a thick dewatered mass. The 70 liquid overflows the edge of the tank and is caught by the overflow launder.

I claim:

1. A thickener comprising a tank, a curved blade therein arranged adjacent the bottom thereof and having a plurality of convolutions in a plane intersecting its axis of rotation at an angle, the successive convolutions of the blade lying closer together as the blade progresses inwardly, and means 75 for rotating said blade about said axis.

2. A thickener comprising a tank, means therein rotatable about a vertical axis for moving settled material toward the center of the tank and means at the center of the 85 tank acting in conjunction with said rotatable means for pressing the collected material together.

3. A thickener comprising a tank, means therein rotatable about a vertical axis for 90 moving settled material toward the center of the tank and a plate overlying and arranged in close proximity to said means at the center adapted to prevent upward movement of the collected material.

4. A thickener comprising a tank, a horizontally rotatable curved element therein terminating at its inner end adjacent the center of the tank and a plate overlying the inner end of said element and bearing 95 against the upper edge thereof.

5. A thickener comprising a tank, a horizontally rotatable spiral blade therein arranged adjacent the bottom of the tank and extending from adjacent the periphery to 105 adjacent the center of said tank and a plate, overlying the inner end of said blade and arranged in close proximity to said blade.

6. A thickener comprising a tank having an outlet in the bottom thereof, rotatable 110 means within said tank for moving material toward said outlet and a plate arranged on and directly over said means and directly above said outlet whereby lateral pressure toward said outlet is exerted against the 115 underlying material.

7. A thickener comprising a tank having an outlet in the center of the bottom thereof, rotatable means within said tank for continuously moving material toward said outlet, and a plate overlying and in contact with the inner ends of said means and forming therewith a chamber into which the collected material is forced.

8. A thickener comprising a tank having 125 an outlet in the center of the bottom thereof, a horizontally rotatable element therein having a curved forward face extending from adjacent the periphery of the vessel to adjacent said outlet and a plate overlying 130

and in contact with the inner portion of said element whereby a laterally open chamber is formed.

9. A thickener comprising a tank, rotatable means therein for moving material toward the center of the tank, a plate overlying and secured to said means at the center and an imperforate conical structure arranged on said plate for deflecting material therefrom.

10. A thickener comprising a tank having an outlet in the center of the bottom thereof, a horizontally rotatable spiral blade arranged in said tank adjacent the

bottom and extending from adjacent the periphery of the tank to adjacent said outlet, and a circular plate overlying the inner end of said blade and in engagement therewith for the purpose of pressing the collected material together.

In testimony whereof, I have hereunto set my hand at San Francisco, California, this 15th day of July, 1914.

ALBERT E. VANDERCOOK.
